UNITED STATES PATENT OFFICE.

EBENEZER A. W. JEFFERIES AND JEROME R. GEORGE, OF WORCESTER, MASSACHUSETTS, ASSIGNEES TO MORGAN CONSTRUCTION COMPANY, OF WORCESTER, MASSACHUSETTS, A CORPORATION OF MASSACHUSETTS.

GAS-PRODUCER.

1,097,757.

Specification of Letters Patent.

Patented May 26, 1914.

Application filed December 1, 1910. Serial No. 595,160.

To all whom it may concern:

Be it known that we, EBENEZER A. W. JEFFERIES and JEROME R. GEORGE, both citizens of the United States, residing at 5 Worcester, in the county of Worcester and Commonwealth of Massachusetts, have invented a new and useful Improvement in Gas-Producers, of which the following is a specification, accompanied by a drawing, 10 forming a part of the same.

Our invention relates to an improvement in that class of gas producers employed for the production of fuel gas and particularly that class of fuel gas producers which employs within the heating chamber means to effect the rotation of the fuel contained in the lower portion of the heating chamber, and it consists in the employment of an annular beveled shelf or screen supported by 15 the inner wall of the gas producing chamber and above the plane of the rotating means, as hereinafter described and pointed out in the annexed claims.

In the accompanying drawing we have 20 represented a side view of a gas producer embodying our invention, having the lower portion shown in central section.

Several parts hereinafter referred to are indicated by reference characters.

30 The heating chamber 1 is inclosed in a casing 2 preferably cylindrical and supported upon columns 3. The upper portion of the casing is preferably lined with a refractory material 4 and the lower portion is surrounded by an annular water chamber 5. Inclosed within the lower portion of the casing are means for rotating the fuel, consisting, in the present instance, of hollow radial arms 6, 6 attached to a central rotating dome or pipe 7 which, in the present instance, is attached to an ash pan 8 spaced below the gas producer casing and rotated by any suitable means, not shown, upon the supporting rollers 9. A blast of air and 45 steam is supplied through a supply pipe 10 to the hollow dome 7, from which it passes to the interior of the heating chamber through openings or slits 11, 11 in the top of the dome and also through slits 12, 12 formed in the tops of the hollow arms 6. As the fuel is moved around within the lower portion of the casing by the rotation of the arms 6, 6, its outward movement, which 50 would tend to produce a wedging action of

the fuel against the inner sides of the casing, is restrained by means of an annular band 13 attached to the outer ends of the radial arms 6.

The above construction comprises no part of our present invention, which relates to the employment above the rotating arms 6, 6 and annular band 13 of an annular shield 14, preferably formed in sections 14^a and attached to the inner side of the casing by means of bolts 15. The upper surface 16 of the shield 14 is beveled, forming an obtuse angle with the inner side of the casing, so that fuel in its downward movement will be carried toward the center of the heating chamber. The under side of the shield is 70 provided with a recess 17 to receive the upper edge of the band 13 and allow the lower edge 18 of the shield to overhang the upper edge of the band 13 and extend downward into a lower horizontal plane. 75

As combustion proceeds and ashes are removed from the ash pan 8, the mass of fuel in the heating chamber 1 gradually moves downward until it comes in contact with the beveled surface 16 of the annular shield, 80 which causes the fuel to be crowded toward the center of the chamber and to fall inside the annular band 13 and between the radial arms 6, 6.

The beveled surface 16 affords a partial 85 support for the superimposed mass of fuel, and while the contents of the heating chamber below the shield are being forcibly rotated by the arms 6, 6, the rotative movement of the fuel above the shield is reduced 90 by the support afforded by the shield, thereby producing a cleavage of the fuel and preventing the formation of clinkers. The shield also, by overhanging the edge of the band 13, prevents the access of coal between 95 the band and the wall of the producer. The shield is preferably made in sections, which are normally slightly separated in order to provide for the necessary expansion of the sections during the operation of the producer, and also to enable individual sections to be replaced when they may have become 100 burned by the heat of the producer. The shield is also protected from the heat of the producer by being attached to a metallic wall 105 of the casing which is surrounded by the annular water chamber 5 by which the heat of the casing and of the shield is reduced.

We claim,

1. In a gas producer, a metal casing inclosing the lower part of a heating chamber, and an annular shield detachably attached 5 only to said metal casing and having an oblique or beveled upper surface.
2. In a gas producer, a casing inclosing the lower part of the heating chamber, and an annular shield detachably attached only 10 to said casing, said shield having an upper beveled surface and having a horizontal lower edge provided with an annular recess.
3. In a gas producer, a casing inclosing the lower part of a heating chamber, an annular shield detachably attached to said 15 casing only, with the upper surface of said shield beveled and the lower surface horizontal with a concave recess, and a rotatable annular plate with its side slightly inclined from a vertical and with its upper edge 20 entering said recess.
4. In a gas producer, a metal casing inclosing the lower part of a gas producing chamber, means for water cooling said casing, a shield detachably attached to the water cooled wall of said casing, said shield 25 consisting of sections having beveled upper surfaces and horizontal lower recessed surfaces.
5. In a gas producer, a casing inclosing a heating chamber, an ash pan spaced below 30 said casing, arms inclosed in the lower part of said casing, means for rotating said arms about a vertical axis, an annular band attached to the ends of said arms and inclosed within said casing, and a shield above 35 said arms and attached to said casing, said shield having a beveled upper surface, with the inner lower edge of said shield extending below the upper edge of said band. 40
6. In a gas producer, a casing inclosing a heating chamber, arms inclosed in the lower part of said casing, means for rotating said arms about a vertical axis, an annular band attached to the ends of said 45 arms and inclosed within said casing, and a shield above said arms and attached to said casing, said shield having a beveled upper surface, with the inner lower edge of said shield extending inwardly beyond the upper 50 edge of said band.

Dated this 28th day of November 1910.
